UNITED STATES PATENT OFFICE.

NICOLA MANCINI, OF LONG ISLAND CITY, NEW YORK.

DESIGN FOR A CARRIAGE.

48,121.

Specification for Design.

Patented Nov. 9, 1915.

Application filed June 30, 1915. Serial No. 37,376. Term of patent 7 years.

To all whom it may concern:

Be it known that I, NICOLA MANCINI, a subject of the King of Italy, residing at Long Island City, in the county of Queens and State of New York, have invented a new, original, and ornamental Design for Carriages, of which the following is a specification, reference being had to the accompanying drawing, forming part thereof.

The figure is a side elevation of a carriage, showing my new design.

I claim:

The ornamental design for a carriage, as shown.

NICOLA MANCINI.

Witnesses:

FRANCESCO BATTISTA,
PARQUALE AVALLONE.
